SURGICAL BRACE

Robert C. Blair, Jr., Orlando, Fla.

Application October 23, 1953, Serial No. 387,870

4 Claims. (Cl. 128—87)

1

This invention relates to an orthopedic appliance and more particularly to an adjustable means for use with such devices as cervical appliances or the like.

A primary object of the invention is the provision of a device of this character which will provide for the most minute and accurate possible adjustments.

As conducive to a clearer understanding of this invention, it may here be pointed out that in orthopedic appliances such as those where it is desired to retain portions of the body in fixed relation during the healing of fractures or the like, extreme accuracy of positioning is essential.

This is particularly true in the case of cervical appliances designed for proper positioning of the head during the healing of the fracture of the cervical vertebrae or the like.

A particular object of this invention, therefore, is the provision of a device of this nature which may be adjusted to the body of the patient for securing the head and neck in the desired relationship with the most minute accuracy, and which may be further adjusted to the individual's needs with almost micrometric exactness.

Still further objects reside in the combinations of elements, arrangements of parts and features of construction, all as will be more fully pointed out hereinafter and disclosed in the accompanying drawings, wherein there is shown one form of this inventive concept.

In the drawings:

Figure 1 is a side elevational view of one form of orthopedic appliance embodying the adjusting features of the instant invention shown as applied to the head of a human being;

Figure 2 is a front elevational view of one of the adjusting means for the device;

Figure 3 is a rear elevational view showing the rear adjusting member of the device;

Figure 4 is a sectional view taken substantially along the line 4—4 of Figure 2, as viewed in the direction indicated by the arrows;

Figure 5 is a sectional view taken substantially along the line 5—5 of Figure 4, as viewed in the direction indicated by the arrows;

Figure 6 is a sectional view taken substantially along the line 6—6 of Figure 2, as viewed in the direction indicated by the arrows;

Figure 7 is a sectional view taken substantially along the line 7—7 of Figure 2, as viewed in the direction indicated by the arrows;

Figure 8 is a sectional view taken substantially along the line 8—8 of Figure 2;

Figure 9 is a sectional view taken substantially along the line 9—9 of Figure 3, as viewed in the direction indicated by the arrows; and

Figure 10 is a side elevational view of a constructional detail.

Similar reference characters refer to similar

2

parts throughout the several views of the drawings.

Having reference now to the drawings in detail, the device of the instant invention comprises an orthopedic device including a breastplate 20 of conventional design and a back plate 21, including portions 22 adapted to rest on and overlie the shoulders. Portions 20 and 22 are adapted to be connected by strap members 23 which may include adjusting buckles 24, the latter being secured fixedly to one member as by means of rivets 25 and by releasable means such as snap fasteners 26 to the other member. Similarly straps 27 are provided connecting the rear plate 21 to the breastplate as by means of snap fasteners 28, the straps 27 being adapted to be passed under the arms of the wearer of the appliance.

The particular adjusting means for the chin rest 30 and the neck brace 31 are best shown in Figures 2 and 3. It may here be pointed out that the chin rest 30 is of conventional construction and merely includes a concave plate including inner padding and having upstanding side portions 32 adapted to support the chin to prevent vertical movement of the head.

The head and neck support includes an arcuate portion including ears 34 adapted to extend on opposite sides of the neck, and a head supporting portion 35. Suitable chains 36 may extend from chin portion 30 to the ears 34, or if desired straps may be substituted therefor.

Having now particular reference to the adjusting means for the device and more particularly to Figure 2, there are disclosed as a fixed part of breastplate 20 two identical members 40 which may be referred to as female adapters. An identical member 40a is secured beneath the chin rest 30. All of these members are substantially identical and comprise rectangular blocks, as shown in Figures 6 and 7 respectively. Each of the blocks comprises a rectangular body 41 provided with a plurality of transverse bores 42 which may be of variable number but which, in the illustrative embodiment, are disclosed as three. The member 40 is secured to breastplate 20 in any suitable manner, as by rivets 43.

The inner padding of the breastplate is indicated in Figure 6, as at 20a. An identical construction prevails in the arrangement of member 40a, as shown in Figure 7, and which is affixed to the chin rest 30; the reference characters in Figure 7 being designated, as to corresponding parts, as 41a, 42a and 43a respectively.

Adapted to extend into a selected bore 42 or 42a respectively are two inwardly turned stud members 45, being in opposed relation and comprising the extremities of hairpin members designated as 46. There are three of these members 46, two extending downwardly to the members

49, and the third being oppositely disposed and extending upwardly to the member 40a.

Each of these members is provided with oppositely disposed symmetrically outwardly flared portions 48, and each is provided with a slide lock generally indicated at 50, which is adapted to move on the parallel portions of the member 46 upwardly or downwardly for the purpose of selectively clamping the studs 45 in the associated bores 42 or 42a. The slide locks 50 comprise, as best shown in Figure 8, merely rectangular members provided with aligned parallel bores 51 through which extend the legs of the hairpin members 46.

There is also provided, as best shown in Figure 2, a central or master locking member 55 which is comprised of opposed plate sections 56 suitably secured together and provided with horizontal parallel bores 51 for the reception of all of the legs of the members 46. Between the legs of each member there is provided in the member 55 a recess 57 and a threaded bore 58 for the reception of a screw 59. Seated within the recess 57 is a star washer 60 or the like, of sufficient dimensions to bear against the opposed legs of its associated member 46 for the purpose, when the screw 59 is tightened, of clamping the same tightly against linear movement. The screw 59 may be of any desired type, but are preferably Phillips headed, as shown best in Figure 2, in order to prevent accidental or unauthorized dislodgement.

The arrangement of the adjustment of head plate 31 relative to back plate 21, as best shown in Figure 3, is substantially but not quite identical. There is disclosed as secured to head plate 31 member 40b, identical to member 40a, which in turn carries two studs 45b of a hairpin member 46b which is provided with a slide lock 50b. A central master locking lock 55b is substantially identical in configuration to the lock 55 previously described, but supports U-shaped or hairpin members 65 which are provided with straight ends 66, omitting the studs 45b. The extremities of these members, instead of engaging member 40, engage in blocks 67 each block being provided with a locking screw 70, and each block being secured, as by a rivet 63 or the like, to back plate 21. The blocks 67 are provided with locking screws 70 and locking washers 71 which coat with the legs of the members 65 at their lower extremities in the manner substantially identical to that of the screws 59 previously described.

As best shown in Figure 10, the members 65 are provided with an angular bend 72 in order that the rear adjustment may conform to normal body configuration.

From the foregoing it will now be seen that there is herein provided an improved adjustment for orthopedic appliances, which accomplishes all of the objects of this invention and others, including many advantages of great practical utility and commercial importance.

As many embodiments may be made of this inventive concept, and as many modifications may be made of the embodiment hereinbefore shown and described, it is to be understood that all matter herein is to be interpreted merely as illustrative and not in a limiting sense, all as defined by the appended claims.

I claim:

1. In an orthopedic appliance, comprising breast and back plates, a chin support, and a neck and head rest, an adjusting device for varying the distance between the chin rest and the

breast plate comprised of a pair of spaced blocks secured to said breast plate, said blocks having a plurality of apertures therein, a pair of hairpin members having lugs engaging in said apertures, slide locks on said members; a single block secured to said chin rest and provided with a plurality of apertures, a third hairpin member having lugs selectively engaging in said last mentioned apertures, a slide lock in said third hairpin member, and a master lock plate securing said three hairpin members in a selected location.

2. In an orthopedic appliance, comprising breast and back plates, a chin support, and a neck and head rest, an adjusting device for varying the distance between the chin rest and the breast plate comprised of a pair of spaced blocks secured to said breast plate, said blocks having a plurality of apertures therein, a pair of hairpin members having lugs engaging in said apertures, slide locks on said members; a single block secured to said chin rest and provided with a plurality of apertures, a third hairpin member having lugs selectively engaging in said last mentioned apertures, a slide lock in said third hairpin member, and a master lock plate securing said three hairpin members in a selected location, said master lock plate including bores adapted to surround the legs of said hairpin members and clamping means for engaging said legs.

3. In an orthopedic appliance, comprising breast and back plates, a chin support, and a neck and head rest, an adjusting device for varying the distance between the chin rest and the breast plate comprised of a pair of spaced blocks secured to said breast plate, said blocks having a plurality of apertures therein, a pair of hairpin members having lugs engaging in said apertures, slide locks on said members; a single block secured to said chin rest and provided with a plurality of apertures, a third hairpin member having lugs selectively engaging in said last mentioned apertures, a slide lock in said third hairpin member, and a master lock plate securing said three hairpin members in a selected location, said master lock plate including bores adapted to surround the legs of said hairpin members and clamping means for engaging said legs, said clamping means including set screws and washers adapted to clamp said legs.

4. In an orthopedic appliance, comprising breast and back plates, a chin support, and a neck and head rest, an adjusting device for varying the distance between the chin rest and the breast plate comprised of a pair of spaced blocks secured to said breast plate, said blocks having a plurality of apertures therein, a pair of hairpin members having lugs engaging in said apertures, slide locks on said members; a single block secured to said chin rest and provided with a plurality of apertures, a third hairpin member having lugs selectively engaging in said last mentioned apertures, a slide lock in said third hairpin member, and a master lock plate securing said three hairpin members in a selected location, and a corresponding adjusting device for varying the distance between said back plate and said neck and head rest.
